UNITED STATES PATENT OFFICE.

HENRY C. MAXWELL, OF ROME, NEW YORK.

DESIGN FOR A HARNESS-BREECHING RING.

SPECIFICATION forming part of Design No. 14,584, dated January 20, 1884.

Application filed November 30, 1883. Term of patent 14 years.

To all whom it may concern.

- Be it known that I, HENRY C. MAXWELL, a citizen of the United States, residing at Rome, in the county of Oneida and State of New York, have invented and produced a new and original Design for Harness-Breeching Rings, of which the following is a specification, reference being had therein to the accompanying drawing.
- 10 This design has reference to harness-breeching rings; and it consists in the shape or configuration of the same, as will be hereinafter described, and shown in the drawing hereto annexed.
- 15 The figure of the drawing represents a face view of the design.

Referring by letter to the accompanying drawing, D designates the design, which is in

D-shaped form, the portion A being of semi-circular form, while the portion B is straight; 20 and to the upper portion of said D-shaped part is cast therewith a loop, C, the outer bar of which is on an incline form from front to rear, as shown in the drawing.

Having described my design, what I claim, 25 and desire to secure by Letters Patent, is—

The design for harness-breeching rings herein shown and described, consisting of the D-shaped ring provided with the loop integral therewith.

In testimony whereof I affix my signature in presence of two witnesses.

HENRY C. MAXWELL.
